UNITED STATES PATENT OFFICE.

GYULA GÁL, OF SZEGED, HUNGARY, ASSIGNOR OF ONE-HALF TO BALINT GELLEN, OF NEW BRUNSWICK, NEW JERSEY.

RAIL JOINT.

Application filed May 13, 1926. Serial No. 108,824.

This invention relates generally to rails such as used for steam and electric railways and the like.

The invention having more particular reference to a novel type of rail joint which will permit locomotives, cars, or any type and variety of rolling stock to pass from one rail to another without a jolt or jar which ordinarily occurs, and which causes excessive wear to the rails and to the wheels of the rolling stock.

For further comprehension of the invention, and of the objects and advantages thereof, reference will be had to the following description and accompanying drawing, and to the appended claims in which the various novel features of the invention are more particularly set forth.

Fig. 1 of the drawing, shows a perspective view of two rails embodying my improved rail joint.

Fig. 2 is a top plan view thereof.

Fig. 3 is a side elevational view thereof.

The rails 10 and 11, are of common ordinary construction and design such as commonly used for steam and electric railways of all types and varieties.

As a means of jointing the rails 10 and 11, so as to allow the rolling stock passing over the said rails to pass gradually from one of the said rails to the other, the rails 10 and 11 are diagonally cut at their extremities, as designated respectively by the reference numerals 20 and 21.

The rail 10 has cut, or otherwise formed at its center, between the said diagonal cuts 20 and 21, a protruding portion 22, having an enlarged extremity, preferably circular shaped, to engage the aperture 23, cut or otherwise formed in the rail 11, between the said diagonal cuts 20 and 21, to receive and engage the said protruding portion of the rail 10, it being understood that the aperture 23 is suitably shaped for the purpose as above stated. The lower portion of the extremity is cut away or otherwise removed, so as to accommodate the block 24, of any suitable shape, so as to support the extremity of the rail 11. The protruding portion 22 is provided only on the upper portion of the rail and is engaged at its lower surface 24' by the block 24 which is disposed below the projecting portion 22. The block 24 is

separate from the rail and may be removed and replaced by a thicker or thinner block 53 when desired to maintain a smooth fitting relationship between the upper surfaces of the rail ends.

It is obvious that I have provided an improved rail joint, which will allow the rolling stock passing over same to pass gradually from one rail to another for the purpose as hereinbefore stated and set forth.

Having thus described my invention, what I claim as new and desire to protect by Letters Patent of the United States is as follows:

1. A rail joint comprising diagonally cut rail ends, one of the said rails provided with a central protruding portion having an enlarged circular extremity to engage an aperture cut in a second rail, between diagonal cuts at the edges of its extremity, said projecting portion being provided at the upper portion of the rail, and a block adapted to 70 be inserted between said rail ends to engage the lower surface of said projection, said block being removable.

2. A rail joint comprising diagonally cut rail ends, one of the said rails provided with 80 a central protruding portion having an enlarged circular extremity to engage an aperture cut in a second rail, between diagonal cuts at the edges of its extremity, the lower portion of the said extremity of the said 85 second rail being removed and a removable block disposed under said projection adapted to hold the latter and its rail end at a suitable elevation.

3. A rail joint comprising diagonally cut 90 rail ends, a projection on the upper portion of one of said rail ends directed at an angle to the longitudinal axis of said rail, the other of said rail ends being provided with a groove for receiving said projection and 95 having the stock of said rail directly below said groove cut away and a removable block adapted to be disposed below said projection to support the latter and to predetermine the elevation thereof for providing a closely 100 fitting relationship between the upper surface of said rails.

In testimony whereof I have affixed my signature.

GYULA GÁL.
